UNITED STATES PATENT OFFICE.

GABRIELLE DE NOTTBECK, OF NEW YORK, N. Y.

DESIGN FOR A SWING-SEAT.

Specification forming part of Design No. **7,179**, dated February 17, 1874; application filed January 17, 1874.
[Term of Patent 3½ years.]

To all whom it may concern:

Be it known that I, GABRIELLE DE NOTTBECK, of the city, county, and State of New York, have invented a new and original Design for Swings, of which the following is a specification:

My design relates to the seat of a swing; and consists in the figure of a hobby-horse, supported on a platform, *e*, as shown.

The platform is hung, by parts *a b c d*, from posts *g*, set in a base, *f*.

This frame-work forms, however, no part of the design.

The drawing also shows the figure of a rider; but this is no part of the design.

What I claim is—

The design for the seat of a swing, as described and shown.

GABRIELLE DE NOTTBECK.
